UNITED STATES PATENT OFFICE.

FRANK L. CROSS, OF PORT WASHINGTON, NEW YORK, ASSIGNOR TO CROSS PAPER FEEDER COMPANY, A CORPORATION OF MAINE.

SHEET-FEEDING MACHINE.

1,169,129.

Specification of Letters Patent. Patented Jan. 25, 1916.

Application filed August 13, 1914. Serial No. 856,577.

To all whom it may concern:

Be it known that I, FRANK L. CROSS, a citizen of the United States, residing at Port Washington, in the county of Nassau and State of New York, have invented certain new and useful Improvements in Sheet-Feeding Machines; and I do hereby declare the following to be a full, clear, and exact description of the invention, such as will enable others skilled in the art to which it appertains to make and use the same.

The invention relates to paper feeding machines and more particularly to mechanism for interrupting the operation of the sheet handling devices in case the sheet is not presented in proper position.

The object of the invention is to provide novel and improved mechanism by which the devices which operate on the sheets may be thrown out of operation upon the failure of the sheet to be properly positioned without requiring the stopping of the actuating cam shaft or other rapidly moving and comparatively heavy actuating mechanisms.

To this end the invention contemplates the provision of sheet controlled means for disconnecting the various sheet engaging devices from their respective actuating mechanisms so that they are rendered inactive or thrown out of operation while the actuating mechanism continues to be driven. This enables the mechanism to be driven at a high speed and the feed of the sheets to be quickly stopped and to be resumed without the shock and wear on the parts incident to the stopping and starting of the actuating mechanism.

The invention comprises the features of construction and combination of parts hereinafter described and set forth in the claims.

The various features of the invention will be readily understood from an inspection of the accompanying drawings and the following detailed description of the mechanism illustrated therein.

In the drawings Figure 1 is a diagrammatic perspective view of so much of a paper feeding machine as is necessary to show the application of the present invention thereto; Fig. 2 is a side elevation, certain parts being removed; Fig. 3 is a detail of the throw-out mechanism; Fig. 4 is a sectional elevation; Fig. 5 is a detail of one of the cut-outs and Fig. 6 is a detail side

elevation showing certain of the controlling devices.

In the drawings, the invention is shown as embodied in the automatic sheet feeding machine known as the "Cross paper feeder". In this machine a bank of feathered sheets 60 is acted upon by two independently controlled combing wheels which are lowered upon the sheets at regular intervals and each of which is independently disengaged from the bank of sheets by cut-out mechanism controlled by the front edge of the sheet when it is advanced into position to be acted upon by the delivery rolls which carry away the top sheet and deliver it to the devices by which it is brought into proper register at the front guides of the printing press or other machine to which the sheets are to be fed. While the top sheet is being removed from the top of the bank by the delivery rolls, the second sheet is held by 70 tail clamps which are raised from the bank during the action of the combing wheels. The bank of sheets is fed forward to maintain it in proper position with relation to the combing wheels by feeding mechanism 80 the feeding action of which is controlled from the cut-out mechanism through which the combing rolls are raised.

The mechanism thus far referred to is of the usual construction and is substantially 85 the same as that shown and described in Patent No. 812,260, February 13, 1906, with the exception that the bank of sheets is fed from the upper supply table to the lower feed table in the manner illustrated in the 90 patent to Cross, 1,041,747, October 22, 1912, rather than by a traveling loader.

As shown in the drawings the combing wheels are lowered upon the bank of sheets at regular intervals by the cam 2 which engages a roll 3 on the end of an arm 4 carried on the shaft 5. The shaft 5 also carries arms 6 which are connected through links 7 with the frames 8 which carry the combing wheel. The sheet operated cut-out mechanism for each roll comprises a presser foot 9 adapted to engage the bank of sheets and connected by toggle links 10 with a rod 11 carried by the arms 6. The upper end of one of the toggle links is connected by a link 12 with an arm 13 loosely mounted on the cam shaft 14 and held in position indicated in Fig. 4 against the tension of a spring (not shown)

by a latch 15. The latch 15 carries the trip finger 16 adapted to lie across the path of the sheet and a pawl 17 arranged to be brought into engagement with the teeth of a ratchet 18 carried by the cam shaft when the sheet engages the trip finger. When this occurs, the ratchet acts to disengage the latch so that the spring (not shown) may straighten the toggle links 10 thus bringing the presser foot 9 down on the bank of sheets and raising the combing wheel. The presser foot and combing wheel are raised and held in raised position during the delivery of the sheet by the cam 2.

15 The delivery rolls comprise lower rolls 19 and upper drop rolls 20 which are carried by arms 21 secured to a rock shaft 22. The drop rolls are raised and lowered at proper intervals by a cam 23 secured to the cam shaft 14, and engaging the roll 24 carried by an arm 25 secured to the rock shaft 22. The sheet is advanced by the delivery rolls to the supplemental delivery or forwarding rolls by which the sheet is advanced into position at the front guides 28 of the press. The supplemental delivery rolls comprise lower rolls 26 which are driven in unison with the lower delivery rolls 19 and upper drop rolls 27 carried by arms 28 secured to a rock sleeve 29. The drop rolls 27 are raised and lowered at proper intervals by a cam 30 secured to the cam shaft 14 and engaging a roll 31 carried by a lever 32. The lever engages one end of the link 33 the other end of which is connected to an arm 34 on the rock sleeve 29, the end of the link being held in engagement with the lever by a spring 35.

20 The mechanism for raising the tail clamps comprising a bar 36 corresponds to the vertically movable bar of Patent No. 812,260. One end of this bar is pivoted to a lever 37, the lower arm of which is provided with a pin 38 engaged by the notched end of a link 39. The link 39 is pivoted to the lower end of a lever 40 the upper end of which carries a roll 41 engaging a cam 42 on a cam shaft 14. When the end of the link 39 is in engagement with the pin 38, the cam 42 acts 25 to raise and lower the tail clamps at proper periods in the cycle of operations of the machine.

25 The mechanism for feeding the bank of sheets comprises a swinging lever 43 the lower end of which is connected by link 44 with a pawl and ratchet mechanism similar to that shown in Patent No. 812,260 or Patent No. 1,041,747. The lever is operated upon by a spring 45 which tends to force it in a direction to feed the bank of sheets and is moved in the opposite direction against the tension of the spring by a link 46 one end of which is connected to a crank pin 47 on the end of the cam shaft 14, and the other 30 end of which is provided with a slot 48 en-

gaging the pin 49 on the lever. The forward or feeding movement of the lever 43 is controlled through a ratchet bar 50 connected to the lower end of the lever and arranged to be engaged by a stop pawl 51 when the combing wheels are thrown out. The stop pawl is mounted on a collar 52 loosely mounted on the shaft 53 and forced in a direction to engage the teeth of the ratchet bar by a spring 54. The pawl is raised and lowered through an arm 55 mounted on the shaft 53 provided with a pin 56 arranged in a notch in the collar 52. The end of the arm 55 is connected by a spring 57 with one arm of a bell crank lever 58 which is loosely mounted on the cam shaft. The other arm of the bell crank lever is provided at its upper end with a notch engaging a pin 59, which projects from one of the arms 13. The spring 57 forms a yielding link through which the pawl 51 is raised when the cut-out mechanism is re-set or moved into its normal position indicated in Fig. 4. When the combing wheel is raised the arm 13 and lever 58 move toward the right in Fig. 4 thus lowering the arm 55 so that the pawl 51 may engage the ratchet bar and arrest the feeding of the lever 43. The yielding link or spring 57 is used to connect the bell crank lever 58 and arm 55 for a reason which will appear hereafter.

35 In embodying all the features of the present invention in a machine having the general construction above described, throw-out mechanism is provided which is rendered active in case a sheet is not properly positioned at the front guides and which when rendered active disconnects the various devices which operate on the sheets from their prospective actuating cams so that their regular operation upon the sheets is interrupted and the feed of the sheets discontinued until the throw-out mechanism is re-set by the operator. It is necessary in 10 machines of the character described that the lowering of the combing wheels and of the drop rolls shall be properly timed in the cycle of operations, and this timing is determined by the respective operating cams. It 110 is important therefore that re-setting of the throw-out mechanism which re-establishes operative connection between the various parts and their operating cams should be properly timed. Timing means is accordingly provided for preventing re-setting of the throw-out mechanism except at a pre-determined point in the cycle of operations of the machine.

40 In the construction shown the means for disconnecting the mechanism for raising and lowering the combing rolls from the actuating cam comprises a latch arm 60 projecting from a rock shaft 61 and adapted to engage the upper end of a projecting arm 115

62 formed on the arm 4 through which the combing wheels are raised and lowered. The latch arm normally extends in position above and out of the path of the arm 62 but may be swung down into the position indicated in Fig. 6 when the arm 4 is on the high part of the cam 2 and when swung into this position will hold the combing wheels and presser feet 9 in raised position while 10 the low part of the cam 2 is passing the end of the arm 4. The rock shaft is forced in a direction to bring the latch 60 into active position by a spring 63 acting on a link 64 connected to one arm of a three-arm 15 lever 65 which is secured to the end of the rock shaft. The rock shaft is held in normal position against the tension of the spring 63 by a link 66 pivoted to one arm of the lever 65 and provided with a latch 67 arranged to 20 engage a fixed shoulder 68. The mechanism for disengaging the latch 67 and thus rocking the shaft 61 to move the latch arm 60 into active position is controlled by the sheet. This mechanism comprises an arm 69 25 secured to a rock shaft 70 and arranged to lift the free end of the link 66. The rock shaft carries a ratchet segment 71 arranged to be engaged by a pawl 72 carried on an oscillating pawl carrying arm 73. The arm 30 73 is oscillated by a cam 74 secured to the cam shaft 14 and engaging a roll on the upper end of the lever 75, the lower end of which is connected with the pawl carrier 73 by a link 76. During the normal running of 35 the machine, the pawl 72 is held out of engagement with the ratchet 71 by a guard arm 77 secured to a rock sleeve 78 which surrounds the rock shaft 70. The guard arm 77 is provided on its upper end with a notch 40 80 engaging a pin 79 on the pawl and is yieldingly held in engagement with the pin by a spring indicated at 80. The rock sleeve 78 carries depending arms 81 to the lower ends of which are pivoted the controller fingers 45 82. These fingers are arranged to play over tongues 83 which are arranged under the front edge of the sheet when in position at the front guides, and which are provided with notches 84 directly back of the front 50 55 edge of the sheet when in this position. When a sheet is properly positioned at the front guides the sheet guides the fingers 82 over the notches 84 so that the pawl 72 is maintained out of engagement with the ratchet 71. If a sheet is not in proper position, one of the fingers 82 will engage the notch 84 and arrest the movement of the guard arm 77 so that the pin 79 of the pawl 72 will pass off of the upper end of the guard arm and the pawl will engage the ratchet 71 thus rocking the rock shaft 70 and disengaging the latch 67. This will cause the rock shaft 61 to be moved to 60 65 bring the latch arm 60 into active position so that it will prevent the lowering of the

combing wheels upon the bank of sheets. The rock shaft 61 also controls or operates the means for disconnecting the other sheet handling devices from their respective actuating cams. The means for disconnecting the drop rolls 27 from their actuating cam comprises a latched arm 85 arranged to engage a notch formed in the end of an arm 86 which is connected with the lever 32. When the roll on the lever is on the high 70 part of the actuating cam 30, the notch in the arm 86 is in position to be engaged by the latch arm 85 as indicated in Fig. 6. The latch arm 85 is connected with the rock shaft 61 through a link 87 which connects 75 the upper end of an arm 88 projecting from the latch arm to one arm of the three-arm lever 65. The means for disconnecting the drop rolls 20 from their actuating cam comprises a latch arm 89 secured to a rock shaft 85 90 and arranged to be brought into the path of a pin 91 when the lowering of the drop rolls is to be prevented. The shaft 90 carrying the latch arm 89 is provided with an arm 92 which is connected by a link 93 with 90 the arm 88 so that the latch 89 is rendered active when the rock shaft 61 is actuated in the manner above described.

The means for disconnecting the tail clamps from their actuating cam comprises 95 a link 94 the upper end of which is connected to an arm 95 projecting from the rock shaft 61 and the lower end of which is connected to the link 39 through which motion is transmitted to the tail clamps from the 100 cam 42. When the shaft 61 is rocked in the manner above described the link 94 acts to raise the link 39 thus disengaging the end of the link 39 from the pin 38 so that the tail clamps will not be raised by the cam 42. 105

The means for rendering the bank feeding mechanism inactive comprises a rod 96 the upper end of which is connected with an arm 97 projecting from the rock shaft 61 and the lower end of which passes through 110 a suitable guide (Fig. 4) and is arranged to engage the arm 55 through which the stop pawl 51 is raised. When the shaft 61 is rocked in the manner above described, the lower end of the rod 96 is depressed and holds the arm 55 in its lower position, so 115 that the stop pawl 51 is not disengaged from the ratchet bar by the re-setting of the cut-out mechanism. The spring 57 yields when the bell crank lever 58 is swung into the 120 position indicated in Fig. 4 to allow the bell crank lever to move without imparting movement to the arm 55.

The throw-out mechanism is so timed that it rocks the shaft 61 just after the cam 2 125 has raised the combing rolls and presser feet and just before the cam 23 lowers the delivery drop rolls 20, the cam 30 at this time being in position to hold the drop rolls 27 in raised position. When the throw-out 130

mechanism operates therefore, the sheet which has been advanced to the cut-out by the combing wheels remains in this position and is not forwarded by the delivery rolls 5 until the throw-out mechanism is re-set and the sheet separating and feeding mechanisms resume their normal operation. The throw-out mechanism may be thus re-set by the operator by drawing the link 66 toward the 10 left in Fig. 1 to reengage the latch 67 or by manipulation of the handle forming one of the arms of the three-arm lever 65. In order that the mechanisms may not be thrown into operation at an improper time 15 in the rotation of the cam shaft which might result in the improper handling of the sheet, means is provided for preventing the re-setting of the throw-out mechanism except at a predetermined point in the rotation 20 of the cam shaft. As shown, this means comprises a locking notch 98 formed in the arm 62 and adapted to engage the end of the latch arm 60 and prevent movement of the rock-shaft 61 while the low part 25 of the cam 2 is passing the roll on the arm 4. This prevents the re-setting of the throw-out mechanism during that period in the rotation of the cam shaft during which the combing wheels or the presser feet 9 would 30 be in engagement with the bank in the normal running of the machine. The mechanism for timing the re-setting of the throw-out mechanism also comprises a locking notch 99 formed in the latch arm 89 and 35 arranged to engage a shoulder 100 formed on the coöperating pin 91. When the low part of the cam 23 is passing the roll 24 on the arm 25 the shoulder 100 on the pin 91 engages the notch 99, and locks the latch 40 arm 89 and the connected rock shaft 61 against return to normal position. When the roll 24 is on the high part of the cam 23, the shoulder 100 is out of the path of the notch 99 as indicated in Fig. 6. There 45 are two short periods during the rotation of the cam shaft when the combing wheels and also the drop rolls are raised and when therefore the rolls 3 and 24 are on the high parts of the cams 2 and 23. In order that 50 the locking notch 99 and shoulder 100 may be in locking relation during one of these periods the high part of the cam 23 has a slightly depressed portion 101 on which the roll 24 rides for a short period just before 55 the cam comes into position to lower the drop rolls. During this period when the cams are in position to maintain both of the drop rolls and the combing wheels in raised position therefore, the notch 99 and 60 the shoulder 100 coöperate to prevent re-setting of the throw-out mechanism. There is but one period therefore in the rotation of the cam shaft when re-setting of the throw-out mechanism is not prevented and 65 the locking devices described therefore form

a timing mechanism for determining the point in the cycle of operations when the throw-out mechanism may be re-set and the normal operation of the machine be resumed.

While it is preferred to employ the specific construction and arrangement of parts shown and described in embodying the invention in the Cross paper feeding machine, it will be understood that this construction and arrangement is not essential to the broader features of the invention and may be varied or modified as found desirable or best suited to the construction of the paper feeding machine in which it is to be embodied. 80

Having explained the nature and object of the invention and specifically described one form of mechanism in which it may be embodied, what I claim is:

1. A sheet feeding machine, having, in combination, combing wheels, mechanism for raising and lowering the wheels, bank feeding mechanism, and sheet-controlled throw-out mechanism for retaining the wheels in raised position and for discontinuing the normal operation of the bank feeding mechanism. 85

2. A sheet feeding machine, having, in combination, combing wheels, mechanism for raising and lowering the combing wheels, delivery rolls including drop rolls, mechanism for raising and lowering the drop rolls, bank feeding mechanism, and sheet-controlled throw-out mechanism for retaining the drop rolls in raised position and for 95 discontinuing the normal operation of the bank feeding means. 100

3. A sheet feeding machine having, in combination, combing wheels, mechanism for raising and lowering the wheels, bank feeding mechanism and sheet controlled throw-out mechanism for discontinuing the normal operation of the bank feeding mechanism. 105

4. A sheet feeding machine having, in combination, combing wheels, tail clamps, mechanism for alternately raising and lowering the combing wheels and tail clamps, and sheet controlled mechanism for retaining the combing wheels in raised position 110 and disconnecting the tail clamps from their actuating mechanism. 115

5. A sheet feeding machine having, in combination, combing wheels, mechanism for raising and lowering the combing wheels, delivery rolls including drop rolls, mechanism for raising and lowering the drop rolls, bank feeding mechanism and sheet controlled throw-out mechanism for retaining the combing wheels and drop-rolls in raised 120 position and for discontinuing the normal operation of the bank feeding means. 125

6. A sheet feeding machine having, in combination, combing wheels, mechanism for raising and lowering the combing wheels, 130

delivery rolls including drop rolls and mechanism for raising and lowering the drop rolls, tail clamps, mechanism for intermittently actuating the tail clamps, bank 5 feeding mechanism, and sheet controlled throw-out mechanism for retaining the 10 combing wheels and drop rolls in raised position for disconnecting the tail clamps from their actuating mechanism and for discontinuing the normal operation of the bank feeding means.

7. A sheet feeding machine having, in combination, sheet separating means, sheet delivering means, mechanism for actuating 15 said separating and said delivery means to intermittently operate on the sheets, and sheet controlled throw-out mechanism for disconnecting said means from their actuating mechanisms to discontinue the 20 operation of said means on the sheets.

8. A sheet feeding machine having, in combination, combing wheels, sheet delivery drop rolls, mechanism for raising and lowering the combing wheels and drop rolls, and 25 sheet controlled devices for retaining the combing wheels and drop rolls in raised position.

9. A sheet feeding machine having, in combination, combing wheels, sheet delivery drop rolls, mechanism for raising and lowering the combing wheels and drop rolls, normally inactive devices for retaining the 30 combing wheels and drop rolls in raised position and sheet controlled mechanism for rendering said devices active.

10. A sheet feeding machine having, in combination, means for operating on sheets, mechanism for actuating said means to intermittently operate on the sheets, sheet controlled throw-out mechanism for disconnecting 40 said means from its actuating mechanism to discontinue the operation of the said means on the sheets, and mechanism for timing the re-connection of said means with its actuating mechanism.

11. A sheet feeding machine having, in combination, sheet separating means, sheet delivery means, mechanism for actuating said separating and said delivery means to intermittently operate on the sheets, sheet controlled throw-out mechanism for disconnecting 50 said means from their actuating mechanisms to discontinue their operation on the sheets, and means for timing the re-connection of said means with their actuating mechanisms.

12. A sheet feeding machine having, in

combination, combing wheels, mechanism for raising and lowering the wheels, sheet controlled throw-out mechanism for disconnecting the raising and lowering mechanism, and means for timing the re-setting of the throw-out mechanism.

13. A sheet feeding machine having, in combination, combing wheels, means for raising and lowering the wheels, delivery drop rolls, mechanism for raising and lowering the drop rolls, sheet controlled throw-out mechanism for retaining the combing wheels and drop rolls in raised position, and means for timing the re-setting of the throw-out mechanism.

14. A sheet feeding machine having, in combination, combing wheels, mechanism for raising and lowering the wheels, delivery drop rolls, mechanism for raising and lowering the drop rolls, sheet controlled throw-out mechanism for retaining the combing wheels and drop rolls in raised position, and means for preventing the re-setting 75 of the throw-out mechanism during the periods when either the combing wheels or drop rolls are normally lowered.

15. A sheet feeding machine having, in combination, combing wheels, a cam for raising and lowering the combing wheels, delivery drop rolls, a cam for raising and lowering the drop rolls, normally inactive latches for retaining the combing wheels and drop rolls in raised position, and mechanism controlled by the sheet for rendering 80 the said latches active.

16. A sheet feeding machine having, in combination, combing wheels, a cam for raising and lowering the combing wheels, a lever engaged by the cam, a normally inactive latch for engaging the lever to retain the combing wheels in raised position, a lock notch in the lever for engaging the latch, and sheet controlled mechanism for moving 95 the latch into active position.

17. A sheet feeding machine having, in combination, delivery drop rolls, a cam for raising and lowering the rolls, a lever engaged by the cam, a normally inactive 105 latch for engaging the lever to retain the drop rolls in raised position, a locking notch on the latch engaged by a shoulder on the lever, and sheet controlled mechanism for moving the latch into active position.

FRANK L. CROSS.
